UNITED STATES PATENT OFFICE

PETER J. PEEL, OF CHICAGO, ILLINOIS

APPARATUS FOR THE APPLICATION OF ELECTRIC HYDRO-PHYSIO THERAPEUTICS

Application filed June 25, 1927. Serial No. 201,404.

This invention relates to improvements in an apparatus for the treatment of paralytic and other cases requiring treatment by liquid flotation.

5 In ailments of this character movement of the helpless member or part by an operator or manipulator is carried on until the nervous system of the patient which controls the movement of that member, part or 10 parts, takes up the suggestion to an extent whereby the patient may regain use of the member, part or parts. When the patient's member or other part to be treated is utterly helpless it is quite a laborious task for 15 the operator or manipulator to raise or lower or otherwise actuate that member or other part for any appreciable length of time. This has led to treatment of such cases by the use of a method known as liquid flotation wherein the patient is placed 20 in a body of liquid so that the member or part to be treated is immersed, the purpose of this immersion being that the buoyancy of the liquid helps to support the member or 25 part and minimize the effort required to move it.

An object of the present invention is to provide an apparatus with which this method of treating paralytic and other cases by 30 liquid flotation may be carried out in an efficient manner, and without wetting the clothing or person of the operator.

A further object is to provide an apparatus of this character wherein the operator not only is enabled to do his work 35 efficiently without wetting his clothing or person, but he also, at all times, has the member or part being treated in full view.

With these and other objects in view the 40 invention consists in certain novel details of construction and combinations and arrangements of parts all as will hereinafter be more fully described and the novel features thereof particularly pointed out in the appended claims.

In the accompanying drawings,—

Figure 1 is an elevational view of an apparatus embodying the present improvements; and

50 Fig. 2 is a top plan view thereof.

In accordance with the present invention the patient to be treated stands, sits or floats within a tank which is adapted to contain a liquid, the depth of the liquid in the tank being such that the limb or part 55 of the patient to be treated is completely immersed. In this way the buoyancy of the liquid in the tank aids in the motility of the patient's extremity, member or part.

It is, of course, undesirable for the operator to be in the tank also and to avoid 60 this necessity means are provided for permitting the operator to stand or sit on the exterior of the tank and administer manipulative treatment to the patient in the tank. 65 In the preferred embodiment the tank should be approximately four feet high and in the neighborhood of six feet long with a width of three feet. These dimensions need not be adhered to. In order that 70 the operator may have a clear view of the patient from the exterior of the tank, one or more of the sides (10) of said tank are made of transparent material, such as transparent glass. In one side of said tank the 75 glass is formed with two apertures (11) and secured to the said side or wall around those openings are a pair of armlets, elongated gloves gauntlets, (12) or other protective means of ingress through said wall, the attachments of the armlets, gloves, gauntlets or other protective means of ingress through 80 said wall being such that a water-tight joint is formed. Preferably, these openings are arranged in the wall of the tank, as shown, 85 but it will be understood that their location and character depend upon the convenience of the operator, the primary object being to give him access to any part of the body of the patient. Only one pair of such gauntlets is shown, but additional gauntlets or other devices similarly attached may be provided if a larger tank is used or if, for any other reason, they might be deemed necessary or desirable.

When the tank is filled there is considerable pressure on the gauntlets, or other protective means of ingress, probably enough to cause them to collapse and possibly be extruded through the openings (11). For 100

this reason means should be provided for preventing the gauntlets or other protective means of ingress being pushed or pressed outwardly through said openings. Such means may take various forms, the arrangement shown in the present instance simply comprising spiral spring elements (13) extending substantially the length of the gauntlets from the wrist portion to the wall 10 of the tank.

Wall (10) in which openings (11) are provided being transparent the operator would, no doubt, be able to see within the tank sufficient for his purposes. However, 15 in order that an ample quantity of light may penetrate the liquid it is preferred that all four side walls of the tank be of transparent material.

It will be understood that the embodiment 20 illustrated and described may be modified in various respects without departing from the spirit of the present invention.

The present invention, in its broadest aspect, consists in the provision of a tank 25 whose interior, when filled with liquid, is accessible to the operator outside of the tank permitting full view of the patient while inside of the tank and permitting manipulative treatment without wetting the clothing 30 or person of the operator.

If ample light be provided in or on the interior of the tank the necessity of providing large areas of transparent materials in the walls of the tank might be eliminated.

35 Sufficient light could be provided in some artificial way so that it will be necessary to provide only an opening with a transparent closure in an otherwise opaque wall of the tank. This alternate provision to be at the 40 discretion of the patentee.

For such cases as may require electrical, thermal, or light treatment suitable means for the administration of such treatment may be attached, installed or applied in, through 45 or over the walls of said tank in such manner as shall be best adapted therefor by the operator.

What I claim is:

1. An apparatus of the character described, 50 comprising a tank adapted to contain a liquid in which the patient's member or part to be treated may be immersed, one wall of said tank being transparent, and means attached to a wall of the tank below the normal 55 level of liquid therein by which an operator on the exterior of the tank may grasp the patient's immersed member or part with his hand and manipulate it without the escape- 60 ment of the immersing liquid and without wetting the clothing or person of the operator.

2. An apparatus of the character described, 65 comprising a tank adapted to contain a liquid in which the patient's member or part to be treated may be immersed, the interior of

said tank being visible from the outside thereof, and means attached to the tank below the normal level of liquid therein by which an operator may grasp the patient's immersed member or part with his hand for the purpose 70 of control or manipulation, and without wetting the clothing or person of the operator.

3. An apparatus of the character described, 75 comprising a tank to contain a liquid in which the patient's member or part to be treated may be immersed, the side walls of said tank being transparent, and a pair of gauntlets attached to one wall of the tank below the normal level of liquid therein into which an operator on the exterior of the tank 80 may project his hands and arms through said wall, whereby he may grasp the immersed limb or part of the patient in the tank for the purpose of administering manipulative treatment, and without wetting the clothing 85 or person of the operator.

4. An apparatus of the character described, 90 comprising a tank adapted to contain a liquid in which a patient's member or part to be treated may be immersed, the side walls of said tank being transparent, and a pair of gauntlets attached to one wall of the tank into which an operator on the exterior of the tank may project his hands and arms whereby he may grasp the immersed limb or part 95 of the patient in the tank for the purpose of administering manipulative treatment without wetting the clothing or person of the operator, and means for holding said gauntlets distended in the tank when the operator's 100 hands are withdrawn.

5. An apparatus of the character described, 105 comprising a tank adapted to contain a liquid in which the patient's member or part to be treated may be immersed, said member or part when so immersed being visible from the exterior of the tank, and means below the normal level of liquid in said tank for permitting an operator to grasp the immersed member or part with his hand for manipulative treatment, and without wetting the clothing or person of the operator.

6. An apparatus of the character described, 115 comprising a tank adapted to contain a liquid in which a patient's member or part to be treated may be immersed, one wall of said tank having a transparent portion through which the immersed member or part is visible from the exterior of the tank, and means below the normal level of liquid in said tank for permitting an operator on the exterior of the tank to treat said immersed member or part by manipulation with his hand, and without wetting the clothing or person of the operator.

7. An apparatus of the character described, 120 comprising a tank adapted to contain a liquid in which the patient's member or part to be treated may be immersed, being equipped 125 with suitable means for the administration 130

of electrical, thermal or light treatments at discretion of operator, one wall of said tank having a transparent portion and a pair of armlets, gauntlets, gloves, or other protective means of ingress attached thereto and means for holding said gauntlets or other means of ingress, distended in the tank when the operator's hands are in or withdrawn from such apparatus, permitting an operator on the exterior of the tank to administer treatment to patient within the tank without wetting the clothing or person of the operator, thereby enabling him to more conveniently and efficiently administer manipulative treatment by the flotation process.
